CLAIM

The ornamental design for left or right handed scissors, as shown and described.

DESCRIPTION

FIG. 1 is a front elevation of the scissors showing my new design;

FIG. 2 is a rear elevation thereof;

FIG. 3 is a top plan view thereof;

FIG. 4 is a bottom plan view thereof;

FIG. 5 is a right side elevation thereof;

FIG. 6 is a cross sectional view of the thumb handle taken along the line VI—VI of FIG. 2;

FIG. 7 is a cross sectional view of the finger handle taken along the line VII—VII of FIG. 2;

FIG. 8 is a perspective view of the scissors shown on a reduced scale.
